UNITED STATES PATENT OFFICE

WILLIAM H. BAHAN, OF GREENVILLE, SOUTH CAROLINA

ADJUSTABLE GRIPPER FOR SHUTTLES

Application filed May 4, 1929. Serial No. 360,457.

This invention relates to an improved shuttle and more especially to means for holding the bobbin or quill in the shuttle in perfectly alined position.

5 An object of my invention is to provide improvements in a shuttle designed to hold the bobbin in perfect alinement with the shuttle and providing means for adjusting the bobbin holding means, so that the bobbin will 10 be held at all times parallel to the shuttle.

Another object of my invention is to provide improvements in a shuttle which comprises a clamp for holding the base portion 15 of the bobbin with means for inserting the clamp to cause the same to fit perfectly in the shuttle, and means for elevating the clamp when the same becomes worn so as to cause a bobbin to be held in a perfectly parallel position with the shuttle.

20 I am aware that heretofore in shuttles of the conventional type that due to the fact that the bobbin or quill is forced into the clamp under great pressure, that the portion of the quill guide or bobbin guide as it is sometimes called, which supports the lower 25 edge of the clamp for holding the base of the bobbin becomes worn, and also the lower edge of the clamp for holding the bobbin becomes worn, and this allows this clamp which holds 30 the base of the bobbin or quill to sag downwardly and therefore becomes out of alinement with the main portion of the shuttle, and this will cause defective weaving, and a low class of cloth to be produced. By means 35 of my invention I can adjust the clamp for holding the base of the bobbin or the quill to return it to normal position, which has heretofore been impossible with the conventional structure.

40 Some of the objects of my invention having been stated, other objects will appear as the description proceeds, when taken in connection with the accompanying drawings, in which—

45 Figure 1 is a plan view of one end of the shuttle showing my improvements in full and dotted lines;

Figure 2 is a longitudinal cross-sectional view taken along the line 2—2 in Figure 1;

50 Figure 3 is an exploded perspective view

of my improvements as applied to a shuttle;

Figure 4 is a modified form of my invention and showing different means for accomplishing the same results;

Figure 5 is a longitudinal cross-sectional view taken along the line 5—5 in Figure 4;

Figure 6 is an exploded perspective view of the structure shown in Figures 4 and 5;

Figure 7 is a modified form for accomplishing the same results by means of the structure 60 as shown in the Figures 4, 5 and 6;

Figure 8 is a plan view of a portion of a shuttle equipped with still another modified form of my device for adjusting the position of the parts for holding the bobbin;

Figure 9 is a longitudinal cross-sectional view taken along the line 9—9 in Figure 8;

Figure 10 is an exploded perspective view of the structure shown in Figures 8 and 9;

Figure 11 is a modified form of the structure shown in Figure 10;

Figure 12 is an end view of Figure 11 looking from along the line 12—12 in Figure 11;

Figure 13 is a plan view of Figure 11;

Figure 14 is a plan view of one end of the shuttle showing another modified form of my means for adjusting the position of the bobbin holding means;

Figure 15 is a longitudinal cross-sectional view taken along the line 15—15 in Figure 14;

Figure 16 is an exploded perspective view of the parts which are adapted to be mounted in one end of the shuttle and which is shown in Figures 14 and 15.

Referring more specifically to the drawings the numeral 10 indicates the shuttle proper which has the cavity 11 formed longitudinally thereof, and opened at the top side with the portion 12 of the shuttle being not cut-away and on this portion 12 the means for holding the base of a bobbin or quill are mounted. The gripper 13 for holding the base of the bobbin has the grooves 14 cut on the inner surface of each end thereof into

which the rings on the base of a bobbin or quill are adapted to be fitted, and the bobbin or quill is forced into these grooves 14 under pressure causing the ends of the grippers 13 to spring outwardly to receive the bobbin or quill. This member 13 is a forked member

and has the restricted portion 15 which has coinciding holes therethrough, through which the bolt 16 is adapted to be passed to hold the same in position. The shuttle proper is hollowed out to agree with the contour of the member 13 and the outer edges of the same except at the tip portions which hold the bobbin or quill, are adapted to fit flush against the hollowed out portion in the shuttle. I provide a quiller or bobbin guide 17 which is adapted to support the lower edges of the gripper 13 and this has the outwardly turned portions 18 and 19, the lower edges of the gripper being adapted to lie flush with the outer surface of the lower portion of this member 17. This member 17 curves upwardly as at 20 and then inwardly as at 21 to form a sloping surface against which the base of the bobbin is pressed when the same is in position, and these members 21 and 20 cause the bobbin to assume the proper position in the grooves 14. This member 17 has the upper portion 22 which is secured to the shuttle proper by means of the wood screw 23. The mechanism thus far described is of the conventional type and in this conventional mechanism heretofore that has been mounted a non-adjustable wedge, which has been secured between the portions 15 and 15a of the gripper, but in my improvement I provide the member 25 which is formed of a piece of metal bent upon itself to provide the circular portion 26 which has a vertically disposed hole therethrough which is interiorly threaded to receive the threaded bolt 27 which projects downwardly and fits against the portion 17, and has the upper end thereof slotted for the reception of a screw driver or other suitable tool. This member 25 has the upwardly projecting portions 28 and 29 which flare outwardly as at 30 and 31, and then the ends thereof are turned inwardly in alinement with each other and have their ends fitting together, thus forming a wedge like structure which fits in between the gripper at the point where its parallel portions diverge from each other. This member 25 has the hole 31 therein through which the bolt 16 which pierces the holes in the gripper also is adapted to pass thus mounting the gripper and the spreading member 25 on a common pivot. On the upper space of the member 25 I mount the plate member 32 which has the downwardly projecting portion 33 which fits at the rear edge of the projections 28 and 29, and this plate member fits just beneath the portion 22 of the quill guide, so that it is seen that when the parts are mounted in the position shown in Figures 1 and 2, and the bolt 16 and the screw 23 are driven home, that the parts will be held in rigid position.

The member 25 has the hollowed out portion 26a and the screw 27 has the enlarged portion 27a which fits against the member 17.

The member 17 has the hole 17a cut therein, and the shuttle 10 has the hole 27d cut therethrough, and the enlarged head 27a of the bolt 27 fits out around the edges of the hole 17a in the member 17 so that it is possible to insert a screw driver up through the hole 27d into the slot 27b and the enlarged head 27a and adjust the mechanism without removing any of the parts.

It will be seen that due to the great force with which the bobbin or quill is forced into the gripper that a force is exerted which gradually wears the lower edge of the gripper and also wears the plate 17, so as to cause the end portions in which the grooves 14 are cut to gradually sag downward, so that the base of the bobbin is held in a position which is not in the same plane as the tip end of the bobbin, and thus the bobbin is out of alinement, and this will cause seconds and bad weaving. In my structure when this occurs I merely take a screw driver and turn the screw 27 to the right and this presses the lower end of the screw against the plate 17, and will raise the member 25 on its pivot and the raising operation will force the wedge portion formed by the portions 30 and 31 into the narrow or restricted portion of the gripper 13 which is formed by the parallel portions 15 and 15a, and this will spread the gripper apart and force the gripper against the side walls of the cavity in which it fits, and will therefore hold the gripper in a rigid position, and will also raise the gripper up to a point where it is in perfect alinement, and thus render the entire shuttle practically as good as new.

In Figures 4, 5, 6 and 7 I have shown a slightly different embodiment of my invention, in which the parts 10 to 23 are the same as the structure shown in Figures 1, 2 and 3. But I have provided a different means for spreading the gripper, and for elevating the same which is shown by means of the member 40 which is adapted to be pivotally mounted on the bolt 16 between the portions 15 and 15a of the base of the gripper, and this member 40 has the projection 41 thereon, and has the longitudinally and horizontally extending bolt 42 which has the nut 43 thereon, with the washer 44 and the wedge member 45 mounted loosely on said bolt, by means of having the elongated slot 46 through which the bolt 42 is adapted to pass, and this member 45 has the cam surface 46 which is adapted to press against the cam surface 41 on the member 40, and to raise the same when the nut 43 is driven home. This member 45 has the vertically disposed sloping surfaces 47 and 48, which are adapted to press inwardly between the restricted portion of the gripper and to spread the same laterally to wedge the same tightly in position while at the same time the cams 41 and 46 elevate the member 40 at one end thereof by turning the same on

its pivot 16, and this raises the gripper 13 because the member 40 is adapted to fit snugly between the portions 15 and 15a, and if necessary to be welded thereto, to prevent slippage with respect to the portion 40 and the portions 15 and 15a of the gripper, so that when the portion 40 is elevated the gripper will be elevated therewith, and the pressing in of the member 45 will spread the gripper.

10 In Figure 7 I have shown a slightly modified form of the invention as disclosed in Figures 4, 5 and 6, in which I have the member 50 with the hole 51 therein, which is adapted to be pivotally mounted on the transversely disposed bolt 16 and instead of having the cam surface 41 as appears on the member 40, I provide the cam surface at the lower face thereof, said cam surface being indicated by the reference character 52, and I also have the 15 bolt 42a with the wedge member 45a, with the vertically disposed cam surfaces 47a which acts in the same manner as the cam surfaces 47 in Figure 7, and I have the sloping cam surface 46b integral with the member 45a, but 20 which slopes inwardly and fits against the cam surface 52, and this has a wedging effect which elevates the member 50 along with the gripper 13, and the surfaces 47a, the said gripper forces the same against the side walls of the cavity in the shuttle, thus effecting the 25 same result in a different way as disclosed in Figures 4, 5 and 6.

In both of Figures 6 and 7 I provide the plate 53 which is adapted to fit over the top of the member 40 or 50 as the case may be by means of the slot 54 which is adapted to fit over the top of the member 40 or the member 50 as the case may be. The conventional quiller guide portion 22 is adapted to fit over the top of this plate 53 in both instances. The member 45a has the elongated slot 46a therein, which is similar to the slot 46 in Figure 6. In Figures 8, 9 and 10 is shown another embodiment of my invention, in which the members 10 to 23 are the same as those described in Figures 1 and 2, but the wedging and elevating means are somewhat different as will be presently described.

In this structure I provide the member 60 50 which has a hole 61 therethrough, which is adapted to be pivotally mounted on the transversely disposed bolt 16, and this member is bent upon itself and is therefore capable of being spread apart from its portions, and is 55 adapted to be mounted between the portions 15 and 15a of the gripper, and these portions are indicated by the reference characters 62 and 63, the portion 63 being bent inwardly and forwardly, and has a vertically disposed hole therethrough, in which the set screw 64 is threadably mounted, said set screw being 60 adapted to fit against the plate 17 for purposes of elevating the member 60 when the set screw 64 is turned. This projection in 65 which the set screw is threadably mounted

is indicated by the reference character 65. I provide a plate 66 which is adapted to be mounted on top of the member 60 beneath the portion 22 of the plate which is integral with the quiller guide or bobbin guide portion 21. After the portions 62 and 63 are bent with their sides flush against each other, a tapered hole is cut out of both sections, and the pin 67 is mounted therein, and then the enlarged hole 68 is cut out of the top portion of the members 62 and 63 and coincides with the hole in which the tapered pin 67 is mounted, and the interior of this hole is threaded and the set screw 69 is mounted therein, so that by driving home the set screw 69 the tapered pin 67 will be forced downwardly, and this will spread the portions 62 and 63, and therefore spread the outer surfaces of the gripper against the side walls of the cavity in which the said gripper is mounted. After this spreading operation has been effected or even before it has been effected by turning the set screw 64 the member 60 will be turned on its pivot 16 and this will elevate the gripper 13 especially when the spreading operation has been effected before the elevating operation has taken place.

The pin 64 has the enlarged head 64a with the slot 64b therein adapted to receive a screw driver and the member 17 has the hole 64c therein, and the shuttle portion 10 has the hole 64d therein so that it is seen that a screw driver can be inserted through the hole 64d and the hole 64c to engage the slot 64b in the head 64a so that the mechanism may be 100 adjusted without dismantling the same.

In Figures 11, 12 and 13 I have shown a slightly modified form of the invention as disclosed in Figures 8, 9 and 10. In this modified form I dispense with the elevating mechanisms 64 and 65 as shown in Figure 10 and in lieu thereof I provide the tapered hole 75 in which I mount the tapered pin 76, the lower end of said pin being threaded as at 77 and a cut away portion is cut out of the member 60 and the nut 78 is mounted therein, this cut away portion being perfectly square which prevents the nut from turning, and then when the screw 76 is rotated by means of a screw driver, the lower end of the pin 76 will project against the plate 17 and elevate the member 60 or rather rotate the same on the pivot point 16, and at the same time the portions 62 and 63 will be spread apart from each other, and thus simultaneous spreading and elevation will take place.

In Figures 14, 15 and 16 I have shown still another modified form of my invention, in which the parts 10 to 23 inclusive are the same as in the other structures set forth, and in this structure I have a slightly modified form of wedging and elevating means which comprises the elevating and wedging member 80 which has a hole 81 therethrough

70

110

115

120

125

130

which is pivotally mounted on the transversely disposed bolt 16 in the same manner that the other wedging and elevating members are mounted. This member 80 has the enlarged portions 82 and 83 projecting therefrom, these portions being formed by bending a piece of metal upon itself, and these portions lie flush against each other, as designated by the reference characters 84 and 85, and by having the enlarged portion formed by the outwardly projecting portions 82 and 83, I thus provide a cavity 86 which is vertically disposed and in this cavity the head of the bolt 87 is mounted, said bolt projecting longitudinally outwardly, and has the elevating and wedging member 88 mounted thereon, said wedging and elevating member having the vertically elongated slot 89 therein, which is adapted to fit over the bolt 87. 5

10 This wedging member 88 has the slanting portions 90 and 91 which do not act as cams in this instance, but the portion 88 is adapted to fit into the inwardly and downwardly inclined slot 92 and the portion 93 is vertically disposed which has the slot 89 therein, and the horizontally disposed portion 95 is adapted to rest on the plate 17 so that when the nut 96 on the bolt 87 is driven home it will force the portion 88 into the slot 92 and 15 elevate the member 80, by turning the same on its pivot 16 and this will force the portions 82 and 83 against the inside portions of the gripper 18, and will wedge these portions 82 and 83 into the restricted portion formed by the portions 15 and 15a, and will therefore force the gripper outwardly against the wall of the cavity in which it is placed to take up any wear which may have occurred between the gripper and the wall of the cavity in which it is placed, and at the same 20 time the member 80 by means of the wedging portions 82 and 83 will raise the gripper upwardly with relation to the plate 17 and cause the gripper to be adjusted to a proper position so that it will hold the bobbin or quill held by the grooves 15 in perfect alinement, and that takes up any wear which may have occurred due to the excessive strain caused by the rapid forcing of the quill or bobbin 25 into the gripper where it is held during the weaving operation.

In the drawings and specification, I have set forth a preferred embodiment of my invention, and although specific terms are employed, they are used in a generic and descriptive sense only, and not for purposes of limitation, the scope of the invention being set forth in the appended claims.

I claim:

- 60 1. In a shuttle having a gripper to hold the bobbin, means for adjusting the position of the gripper into horizontal alinement with the shuttle and means for spreading the base of the gripper in said adjusted position.
- 65 2. In a shuttle, a gripper for holding the

bobbin, means for spreading the gripper to cause the same to conform to the cavity in the shuttle in which it is mounted, and means for elevating the gripper to cause the same to assume a position in horizontal alinement with the body of the shuttle. 70

3. In a shuttle, a gripper in said shuttle, a wedge member mounted in said gripper, means for elevating the wedge member to press the same into the gripper to spread the 75 same, and means for holding the said wedge member in adjusted position.

4. In a shuttle, a gripper, a base plate for supporting said gripper, a wedge member mounted in said gripper, alined holes in said gripper and said wedge member, a bolt piercing the holes in said wedge member and said gripper, a set screw mounted in said wedge member and having the lower end thereof resting on said base plate, said set screw being adapted to be rotated to elevate said wedge member and to press the upper end of said wedge member between the gripper to simultaneously spread the gripper to cause it to conform to the side walls of the cavity 90 in the shuttle, and to also elevate the gripper into proper adjusted position. 85

5. In a shuttle, a gripper, a combined base plate and quiller guide mounted in said shuttle, pivoted means for securing the gripper in said shuttle, a wedge member pivotally mounted in the base portion of said gripper, elevating means for the free end of said wedge member, said wedge member being adapted to be simultaneously elevated and 100 wedged into the gripper to simultaneously raise one end of the gripper and to force the side walls of the gripper against the side walls of the cavity in which the same is mounted. 105

6. In a shuttle for looms having a gripper for holding the base of the bobbin, a transversely disposed bolt on which the gripper is mounted, a wedge member in the base portion of the gripper, said wedge member being pivotally mounted at the same point on which the gripper is pivotally mounted, means for elevating one end of the wedge member to spread the gripper and to raise the gripper to proper position. 110

7. In a shuttle, a gripper having a U-shaped base portion, the transversely disposed bolt piercing the shuttle on which one end of the gripper is pivotally mounted, a member mounted in the U-shaped base portion of the gripper and being pivotally mounted on the same point that the gripper is mounted; a cam member on said member which is mounted in the base of the gripper, a longitudinally extending bolt mounted on said last named member, a combined wedge and cam member loosely mounted on said bolt, said wedge and cam member being adapted to simultaneously raise the free end 125 120 115 125 130

- of the gripper and to spread the base portion of the gripper.
8. In a shuttle, a gripper, said gripper being of the conventional type and having a looped base portion, a transversely disposed bolt penetrating said looped portion of the gripper, a wedge member mounted on the inside of the looped portion of the gripper and being pivotally mounted on the same bolt on which the gripper is pivotally mounted, the said wedge member being adapted to spread the said gripper, and a set screw mounted vertically in said wedge member, said set screw being adapted to raise the said wedge member, said set screw being adapted to rest on the conventional quiller guide in said shuttle.
9. A shuttle having a gripper and a combined spreading and elevating member associated with said gripper, said combined elevating and spreading member having means to elevate the position of the gripper and to press the gripper firmly against the inside walls of the cavity in the shuttle.
10. In a shuttle having a quill guide, a gripper having a looped base portion, a wedge member mounted in the base of the gripper and means for adjusting the wedge member to spread the gripper and to adjust the horizontal position of the gripper.
11. In a shuttle for looms and the like having a gripper and a quill guide, a wedge member mounted in said base of said gripper having an approximately U-shaped base, said gripper, said gripper and said wedge member being pivotally mounted on a common pivot, and means for raising the free end of the wedge member to simultaneously spread the gripper and to raise the gripper to adjust the same as to its horizontal position.
12. In a shuttle having the conventional gripper, a quill guide having portions thereof mounted above and below the base of the gripper, a bolt piercing through the gripper, a wedge member mounted on said bolt, means in one end of the wedge member for raising the same to spread the grippers and to raise the gripper to adjust the same as to horizontal position.
13. In a shuttle a gripper therein, means for adjusting the vertical alinement of said gripper with relation to said shuttle, and means for spreading said gripper.
14. In a shuttle for looms and the like, a gripper, a pivoted wedge member mounted in said gripper, means for raising one end of said wedge member, means for adjusting said raising means from the exterior of the shuttle, said raising means and wedge means being adapted to spread the gripper and to adjust its horizontal position with relation to the shuttle frame.
15. In a shuttle having a gripper and quill guide, expanding means for simultaneously raising one end of the grippers and spread-
- ing the grippers to cause the same to conform to the cavity in the shuttle, said means being operable from the exterior of the shuttle.
- In testimony whereof I affix my signature.
